UNITED STATES PATENT OFFICE.

FRIEDRICH HERBST AND GUSTAV SEIDEL, OF HALLE-ON-THE SAALE,
GERMANY, ASSIGNORS TO WILHELM SCHMIDT, OF CHICAGO, ILL.

DOUGH-DIVIDING MACHINE.

SPECIFICATION forming part of Letters Patent No. 269,288, dated December 19, 1882.

Application filed October 5 1882. (No model.) Patented in Germany October 18, 1877, No. 640, and August 4, 1880, No. 15,145.

To all whom it may concern:

Be it known that we, FRIEDRICH HERBST and GUSTAV SEIDEL, both of Halle-on-the Saale, in the Kingdom of Prussia and Empire of Germany, have invented certain new and useful Improvements in Dough-Dividing Machines; and we do hereby declare that the following is a full, clear, and exact description thereof, reference being had to the accompanying drawings, and to the letters of reference marked thereon, which form a part of this specification.

This invention has for its object to produce a machine in which to divide a lump of dough into multiple parts of equal weight for small bakings; and it consists of the novel devices and combinations of devices hereinafter described and specifically claimed.

In the accompanying drawings, Figure 1 represents a perspective view of the machine. Fig. 2 represents a vertical longitudinal section of the machine; Fig. 3, a vertical transverse section of the same; Fig. 4, a detached partial section and plan of the table and cutter-frame; Fig. 5, a plan view of the machine; Fig. 6, a side elevation, and Fig. 7 an end elevation, of the machine; and Fig. 8, a plan of the cutter-frame and follower-disk.

Corresponding letters in the several figures of the drawings designate like parts.

The frame consists of a cylindrical table, A, that has square flanges to its top and bottom edges, and is bolted upon two stands, B and B', each composed of two corner-posts that are connected by cross-braces, and both stands are connected again at their base by a tie-rod, a, and screw-nuts b. Under the middle portion of table A is bolted a saddle-plate, C, having an eye in its center, which is bored out to form the guide for a vertical bar, d, that, with its upper flanged head, is secured to the bottom of a disk, D.

A cutter-frame, E, is formed of a series of sheet-metal rings, e and e', that are concentrically connected by radial sheet-metal plates, e, in a manner to form a multitude of openings of equal area that have vertically-parallel sides. The external edges of the radial plates e are downwardly extended and fitted into grooves

in the upper inner face of cylindrical table A in a manner that the cutter-frame E stands above table A and is rigidly supported thereon. The inner ring, e, of the cutter-frame E is sustained besides by four rods, f, that are either slotted on top for inserting the cutter-ring edge, or have said cutter-ring edge secured thereto in any suitable manner, are passed through holes in disk D, and, with their lower screw-threaded ends, are inserted into holes in a ring, g, that is fitted over the eye-hub of saddle-plate C, and are adjustably supported thereon by double nuts h. The disk D, that vertically moves in the cylindrical opening of table A below cutter-frame E, has secured upon its top face a series of followers, i, the upper faces of which are fitted snugly into the openings of the cutter-frame, so as to slide therein, and when raised to their uppermost position to form a perfectly level and smooth surface with the upper edges of the cutter-plates. The lower end of bar d is pivotally connected by links j with the crank K of shaft F, that is mounted in journal-boxes of stands B and B', and upon the overhanging end of which shaft is secured a hand-lever, G, that has an arm, H, for a counter-weight, I. This arm H has secured a toe-plate, l, which will strike upon a bracket, m, of stand B' for preventing the followers i from rising above the cutter-frame E, and a cushion may be attached either to such toe-plate l or to bracket m, that will make the striking of these parts noiseless. The counter-weight I is to be heavy enough not only to raise and hold the followers i to their uppermost position, but such counter-weight is to exert a sufficient overpressure to require a considerable force upon such followers before yielding.

A ring, L, is bored out to fit snugly over the cutter-frame. This ring L, by two rods, M, that are guided in lugs or flanges n of stands B and B', is rigidly connected with yoke N, the center of which is bored out to slide upon rod d. Two bolts, o, with slotted eye-heads, are passed through holes in yoke N, intermediate of rods d and M, and are secured by screw-nuts, and bars p are pivotally connected with one end to bolts o, and with their opposite ends to crank

q of shaft *O*. This shaft *O* is mounted in journal-boxes of stands *B* and *B'*, and has rigidly secured upon its overhanging end a long hand-lever, *T*, which, being turned toward the left, 5 will raise the yoke *N* and ring *L*.

Upon one end of ring *L* are cast two eye-lugs, *r*, to which are pivotally connected by a fulcrum-bolt, *s*, the hinge-extensions of the cover *P*. This cover *P* has a flat and smooth 10 bottom face that will form a close joint with the top of ring *L*, and has an arched top, and, for combining strength with lightness, it is cast hollow. To its front end the cover *P* has secured a latch, *t*, which will engage with a hook, 15 *u*, that forms part of a short shaft, *V*, pivoted in eye-lugs that are rigid with ring *L*. A crank-handle, *v*, is mounted upon one end of shaft *V*, and a leaf-spring, *w*, is secured against the edge of ring *L*, that holds the hook *u* in engagement with latch *t*. For opening the cover the hook *u* is turned away from latch *t* by depressing the handle *V*.

A spring, *Q*, secured against the rear edge of ring *L*, is coiled around the fulcrum-bolt *s*, 20 and is thence extended to reach over the front end of the cover, where a hook bent to its end is coupled by a short chain, *x*, to a hook, *y*, that is secured to the cover *P*. This spring *Q* will raise the cover as soon as the latch is released, and will strike and hold it against cushioned standards *R* in a nearly vertical position. A knob, *S*, is secured upon the front end of cover *P*, by which to push the cover down upon the ring for closing it.

35 The disk *D* has a series of perforations for any particles of dough to drop through that might work past the followers *i*.

The operation of the machine is as follows, to wit: The machine being in position, as shown 40 by Fig. 7, with the cover *P* thrown open and the followers *i* in their uppermost position, so as to be flush with the upper edges of the cutter-frame, a lump of dough of the desired weight is placed centrally upon the cutter-frame *E*. Now, by grasping the lever *T* and by pushing it toward the left the ring *L* is raised until its upper surface reaches above such dough-lump, when the cover is turned down upon its seat, where it will be automatically locked by 45 the hook *u* and latch *t*. Next, by releasing the lever *T* and then by pulling it to the right the dough will be first pressed out uniformly to fill the space inside of ring *L* between the cover *P* and followers *i*, to be formed into a circular cake 50 of equal thickness, and then by further pressure that will overcome the resistance of counter-weight *I* the followers *i* will sink down between the cutters proportionally as the cover *P* approaches the cutter-frame, and the dough will 55 be pressed into the several compartments between the cutters. As soon as the cover *P* is brought down to bear upon the cutter-frame the cover *P* is to be released from latch-hook *u* and will fly open, when the counter-weight *I* 60 will push the followers *i* upward to regain their original positions, and will raise the divided

dough to the surface. After the dough-pieces have been removed another lump of dough is put into the machine to go through the same operation, and so on until all the dough is divided. 70

The hand-lever *G* is for lowering the followers when the cutters are to be cleaned, or for giving an additional counter-pressure to that brought about by counter-weight *I* when a 75 very small lump of dough or very stiff dough is to be divided, to insure its uniform spreading over the entire surfaces of the cutter-frame before the followers are to yield.

By the above-described arrangement of compressing the dough between the cover and followers that are both vertically movable, and of dividing it by stationary cutters that are forced through the dough while thus compressed, a very accurate dividing is accomplished, 85 and the operation is accelerated to a great extent.

As will be noticed, the machine is very simple and compact in its construction and durable in all its parts. 90

What we claim is—

1. In a dough-dividing machine, the combination of the stationary cutter-frame *E*, reciprocating disk *D*, with followers *i*, and reciprocating ring *L*, with cover *P*, and mechanism, 95 as described, for operating the same, substantially as set forth.

2. In a dough-dividing machine, the cylindrical table *A*, having cutter-frame *E*, in combination with reciprocating disk *D*, having followers *i*, and reciprocating ring *L*, having cover *P*, and mechanism for operating the same, all constructed and arranged substantially as described and shown. 100

3. In a dough-dividing-machine, the stationary cutter-frame *E*, in combination with disk *D*, having followers *i*, and being forced upward by a lever, *G H*, having a counter-weight, *I*, all constructed and arranged substantially as described, for the purpose specified. 105

4. In a dough-dividing machine, the stationary cutter-frame *E*, the disk *D*, having followers *i* and rod *d*, that is connected by links *j* with crank *k* of shaft *F*, and of lever *G H*, secured to such shaft, and having counter-weight *I*, all constructed and arranged substantially as set forth, to operate as specified. 115

5. In a dough-dividing machine, the cutter-frame *E*, composed of rings *cc'* and radial plates *e*, and supported by cylindrical table *A*, and 120 by adjustable rods *f*, resting upon saddle-plate *C*, all constructed and arranged substantially as set forth.

6. In a dough-dividing machine, the combination, with the stationary cutter-frame *E*, of 125 ring *L*, connected by rods *M* with yoke *N*, such yoke being connected by rods *p* with crank *q* of shaft *O*, that has lever *T*, all constructed and arranged to operate substantially in the manner set forth.

7. In a dough-dividing machine, the reciprocating ring *L*, having hinged cover *P*, and 130

being provided with spring Q, combined standards R, and a suitable locking device, all substantially as and for the purpose set forth.

8. In a dough-dividing machine, the combination, with the stationary cutter-frame E, of disk D, having followers i, and being connected with lever G H, having counter-weight I, and of the ring L, having cover P, and being connected with lever T, the whole being constructed and arranged to operate substantially as set forth, for the purpose specified.

In testimony that we claim the foregoing as our invention we affix our signatures in presence of two witnesses.

FRIEDRICH HERBST.
GUSTAV SEIDEL.
